KEYBOARD

Alexander Adolf Carlo Degen, Harrow, England,
assignor to Bell Punch Company Limited, London, England

Application September 10, 1934, Serial No. 743,477
In Great Britain June 11, 1934

9 Claims. (Cl. 235—145)

This invention concerns improvements in and relating to key operated ticket issuing and ticket printing and issuing machines and has for its object to provide an improved key board for the machine which gives satisfactory key operation whilst protecting the keys against damage and, in one form of construction, rendering the key board dust and water proof.

The invention comprises a key operated ticket issuing or ticket printing and issuing machine, provided with a key board that is flush and devoid of all projections.

Further, the invention consists in the provision, in a key operated ticket issuing or ticket printing and issuing machine of a key board comprising a cover plate positioned over and adjacent to the ends of the key levers or stems of the keys to be manipulated in such a manner that the said ends do not extend substantially above the said plate and are operable manually through openings (one for each key) in the plate.

The invention also consists in the provision in a key operated ticket issuing or ticket printing and issuing machine, of an elastic or flexible membrane mounted immediately under one or more openings in a key board cover plate and over the ends of the key levers or stems to be manipulated, in such a manner as to be flexed in operating any of the keys through the opening by pressure applied to the said key through the membrane.

In order that the invention may be fully understood, reference is directed to the accompanying diagrammatic drawing, in which:—

Figure 1 is a sectional side elevation of a machine provided with a key board constructed in accordance with the invention;

Figure 2 is a plan of a portion of the key board shown in Figure 1;

Figures 3 and 4 are views similar to a portion of Figure 1 but illustrating two modifications of the invention; and

Figure 5 is a sectional view similar to Figure 3 but showing a modified construction according to which instead of providing an opening in the cover plate over each key, a single opening common to several keys and extending thereover collectively is provided.

Referring to the Figures 1 and 2, the machine comprises a casing 1 having a front wall 2 and an intermediate wall 3 through slots 4 in which key levers 5 extend from a pivot 6. The upturned ends of the key levers are bent over as shown at 7 and lie just below a rubber membrane 8 disposed parallel to the key board and mounted over

the said upper ends 7 by being clamped below a top cover plate 9 and ledges 10 on the walls 2 and 3. An opening in the form of a finger hole 11 is provided in the plate 9 over each of the respective keys so that a key may be depressed by inserting a finger through one of the said holes and flexing the membrane 8 lying immediately below the finger hole, downwardly by pressure applied to the said key through the membrane. The tops of the keys can be domed as shown to cause the membrane normally to be pressed as a shallow convex projection into the corresponding finger hole.

The membrane may be provided with key designations such as numbers as shown in Figure 2 which appear through the key holes; alternatively the designations can be provided upon the plate adjacent to the finger holes.

Bars may be provided between adjacent keys immediately below the membrane 8 if necessary with keys of light operation to prevent the depression of the membrane in operating one key from inadvertently operating a key adjacent thereto.

The plate 9 can lie flush with the top of the machine or can be stepped in relation thereto.

In the arrangement shown in Figure 3 the membrane 8 is provided with button like projections 12 which are formed integrally with the membrane and which extend through the finger holes 30 so as to lie flush with the top of the plate 9. The key designations can be in either of the forms described with reference to Figures 1 and 2.

In the arrangement shown in Figure 4, the buttons 12 are displaceably mounted in the finger holes and can either be cemented with the membrane 8 or confined by an annular edge 13 of the button between the said membrane and the plate 9. The buttons are substantially flush with the top of the plate 9 and bear the key designations, or such designations can be provided upon the plate 9 adjacent to the finger holes.

The turned over portion 7 of the key lever can be dispensed with if desired particularly in the arrangements shown in Figures 3 and 4 in which the buttons serve to distribute the stresses applied to the membrane during the operation of the keys.

Referring to Figure 5, the single opening hereinbefore referred to which is common to several keys, extending over them collectively, is marked 14, the edges of the opening at the ends thereof only being shown in the figure. As shown the opening extends over 3 keys which are marked 7 as in the previous figures and the rubber mem- 55

brane 8 carries an elongated finger piece 15 corresponding to the button-like projections 12 of the previous arrangement. 9 is the cover plate in which opening 14 is provided.

5 It will be understood, of course, that the invention is equally applicable to keys in which the stems therefor are reciprocatable in guides in lieu of the pivoted mounting of keys shown in the drawing.

10 In all the constructions described, it will be appreciated that projecting key levers, stems or buttons are avoided and the provision of the membrane shown in the various figures makes the key board dust and water proof. Examples of 15 key operated ticket issuing machines to which the invention can be applied are disclosed in United Kingdom patent specifications No. 174,313 and No. 282,581.

15 What I claim and desire to secure by Letters Patent of the United States is:—

20 1. In a key operated ticket issuing or ticket printing and issuing machine, a keyboard comprising a plurality of operable keys, a cover plate positioned over and adjacent to the manipulative ends of said keys, said plate having at least one opening through which said keys can be operated, and a flexible membrane so mounted as to extend 25 between said plate and said keys and permit manual operation of said keys through said opening by flexure of said membrane.

25 2. In a key operated ticket issuing or ticket printing and issuing machine, a key board comprising a plurality of operable keys, a cover plate positioned over and adjacent to the manipulative 30 ends of said keys, a flexible membrane so mounted as to extend between said plate and said keys, and openings in said plate, one to each key and positioned thereover so that each key can be operated through the respective opening by flexure of said membrane.

35 3. In a key operated ticket issuing or ticket printing and issuing machine is claimed in claim 2, such a disposition of the manipulative ends of 40 said keys that the flexible membrane is normally

flexed by said ends in an upwardly domed configuration in each of the openings in the cover plate.

4. In a key operated ticket issuing or ticket printing and issuing machine as claimed in claim 5 2, the provision of button like projections on the flexible membrane, one extending upwardly into each of the openings in the cover plate.

5. In a key operated ticket issuing or ticket printing and issuing machine as claimed in claim 10 2, the provision of finger buttons slidably mounted one in each of the openings of the cover plate above the membrane.

6. In a key operated ticket issuing or ticket printing and issuing machine as claimed in claim 15 2, the provision of flanged finger buttons slidably mounted one in each of the openings of the cover plate above the membrane and with the flange of the button extending between the membrane and the cover plate around the opening.

20 7. In a key operated ticket issuing machine, a keyboard comprising a plurality of operable keys, a cover plate having at least one opening at the tops of said keys, and a flexible membrane closing said opening and overlying the tops of said 25 keys, whereby the keys may be manually depressed by flexure of said membrane.

8. In a key-operated ticket issuing machine, including at least one key, a cover plate having an opening at the top of the key, and a flexible membrane extending across the said opening so as to close it and overlie the top of the key, whereby the key may be manually depressed by flexure of said membrane.

30 9. In a key-operated ticket issuing machine, a keyboard comprising a plurality of operable keys, a cover plate formed to provide access to said keys to permit manual operation of said keys, and a flexible membrane overlying the tops of said keys and underlying said cover plate whereby the keys 40 may be manually depressed by flexure of said membrane.

ALEXANDER ADOLF CARLO DEGEN.
